Primary Examiner—Marcus A. Jackson**Attorney, Agent, or Firm—James A. Wong****[57] CLAIM**

The ornamental design for a detector for hazardous gases, as shown and described.

DESCRIPTION

FIG. 1 is a front, bottom and right side perspective view of a detector for hazardous gases constituting my new design, with the cord broken away to indicate indeterminate length; FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.
